[57] CLAIM

The ornamental design for a vehicle mounted side bar, as shown and described.

DESCRIPTION

FIG. 1 is a top, front perspective view of a vehicle mounted side bar showing my new design;

FIG. 2 is a greatly enlarged cross sectional view thereof, taken along line 2—2 of FIG. 1;

FIG. 3 is a bottom plan view thereof; and

FIG. 4 is a rear elevation view thereof.

The characteristic feature of my design resides in the centrally positioned connector sleeve.
